UNITED STATES PATENT OFFICE.

ARNO A. EWALD, OF OAKFIELD, WISCONSIN.

DESIGN FOR A CASING FOR A COMBINED AIR AND WATER DISPENSER.

55,762.

Specification for Design.

Patented July 13, 1920.

Application filed November 7, 1919. Serial No. 336,480. Term of patent 14 years.

To all whom it may concern:

Be it known that I, ARNO A. EWALD, a citizen of the United States, residing at Oakfield, in the county of Fond du Lac and State of Wisconsin, have invented a new, original, and ornamental Design for a Casing for a Combined Air and Water Dispenser, of which the following is a specification, reference being had to the accompanying drawing, forming part thereof.

The figure is a perspective view of a casing for a combined air and water dispenser showing my new design.

I claim:

The ornamental design for a casing for a combined air and water dispenser, as shown.

ARNO A. EWALD.
